STABILIZED TALL OIL SOAP AND FLOATING
SOAP PRODUCTS

Charles K. Clark and Robert O. Nason, Crossett, Ark., assignors to Crossett Chemical Company, a division of The Crossett Company, Crossett, Ark., a corporation of Arkansas

Application February 6, 1958, Serial No. 714,461

14 Claims. (Cl. 260—97.5)

This invention relates to the manufacture of improved soap products from the black liquor resulting from digestion of pulpwood by the kraft or soda cooking processes. More specifically, this invention relates to the manufacture of floating soaps and tall oil soaps as by-products of pulpwood digestion processes, which soaps are characterized, inter alia, by enhanced resistance to spontaneous heating.

It is well known in the pulp and paper arts that the black liquor produced in the kraft or soda cooking process contains, among other things, the sodium salts of rosin acids and fatty acids. These salts or soaps separate out or float on top of the black liquor during evaporation to recover the alkali values therefrom. The crude floating material obtained during the evaporation is known to the art by various names, e. g., floating soap, soap skimmings and the like.

Crude floating soap is also a source of tall oil. Conventionally, in the production of tall oil from floating soap, the floating soap is split with sulfuric acid to form tall oil and brine. The tall oil is separated out and saponified with aqueous sodium hydroxide. Alternatively, purification by well-known means may be introduced at one or more stages of the process of obtaining the sodium tallate from floating soap. For example, the floating soap may be purified before acidulation or the tall oil may be purified before saponification. Although alkali metal hydroxides and other compounds may be employed for saponification of tall oil, it has been found that only sodium tallate is satisfactory for use in the present invention and for this reason it is intended that any use of the expression "tall oil soap" in this specification and in the appended claims be construed as sodium tallate.

Floating soap and tall oil soap have a number of important industrial applications, one of the more important uses at the present time being as an ingredient in oil well drilling fluids (see United States Patent 2,468,658). For use as an ingredient in oil well drilling fluids and for other industrial uses such as in soaps and lubricants, it is conventional practice to dry the floating soap or tall oil soap and to flake or otherwise comminute the dried soap to form a particulate product. Floating soaps and tall oil soaps may be suitably dried by conventional techniques, for example, by spray drying, drum drying, pan drying, and by combinations of these expedients. Drum drying techniques, however, are normally preferred.

The floating soaps and tall oil soaps currently available are characterized by an outstanding disadvantage, viz., that of spontaneous heating during shipment and storage. In heating spontaneously, these materials undergo a rise in temperature to a level sufficiently above ambient temperatures to cause the particles of floating soap or tall oil soap to fuse into a charred and useless

2

mass. Such spontaneous heating obviously results both in financial loss and a fire hazard.

In copending applications Serial No. 483,369, filed January 21, 1955, and Serial No. 554,681, filed December 22, 1956, it is disclosed that spontaneous heating in floating soap and in tall oil soap may be substantially reduced by compressing the soaps to effect an increase in absolute density. When the compressed products are then comminuted to form the particulate product desired by the art, such product is not only characterized by resistance to spontaneous heating, but is found to be substantially non-dusting and non-caking. Moreover, the compressed product is further characterized by an improved rate of water solubility when compared to the conventional unpressed soaps. Generally, the pressed products will be characterized by an absolute density of between about 0.95 g./cc. and 1.08 g./cc.

Now, in accordance with the present invention, it has been found that spontaneous heating in floating soap and in tall oil soap may be markedly reduced by adding thereto a small or minor amount of a compound selected from the group consisting of ammonium and alkali metal salts of thiosulfuric acid ($H_2S_2O_3$). Conventional unpressed floating soap and tall oil soap and the pressed materials treated in accordance with the processes of the above-identified copending applications are both applicable in and contemplated by the present invention. Although a very substantial improvement in stability against spontaneous heating has been obtained by addition of one of the above-identified stabilizers or inhibitors to conventional unpressed floating soaps and tall oil soaps, a still greater reduction in spontaneous heating may be obtained by the dual treatment of adding such an inhibitor to conventional floating soap or tall oil soap and pressing the resulting mixture according to the pressing operation disclosed in the said copending applications. This dual treatment is preferred because, in addition to effecting a somewhat greater reduction in spontaneous heating, the pressing operation also gives a product having a higher bulk density, less tendency toward caking and dusting and a product which is more readily dissolved in water, as more specifically described in the copending applications.

Generally described, therefore, the invention includes a soap product inhibited against spontaneous heating comprising a material selected from the group consisting of floating soap and tall oil soap obtained by concentration of black liquor resulting from pulpwood digestion processes and containing at least a substantial portion of the impurities naturally present therein and, as the sole essential inhibitor, a minor amount of a material selected from the group consisting of alkali metal and ammonium salts of thiosulfuric acid.

Also generally described, the invention includes a process for producing a soap product inhibited against spontaneous heating which comprises blending with a material selected from the group consisting of floating soap and tall oil soap obtained by concentration of black liquor resulting from pulpwood digestion processes and containing at least a substantial portion of the impurities naturally present therein, as the sole essential inhibitor, a minor amount of a material selected from the group consisting of alkali metal and ammonium salts of thiosulfuric acid. As a further embodiment of the invention, the resulting blend of soap and inhibitor is compressed to increase the absolute density thereof and to thus produce a product of enhanced resistance to spontaneous heating, which possesses improved water solu-

bility, and which is substantially non-dusting and non-caking.

The following examples illustrate preferred embodiments of the instant invention.

The accompanying drawings are related to Examples 3 and 6 and will be explained in connection therewith.

EXAMPLE 1

Floating soap was skimmed off of kraft black liquor and held in large storage tanks for a sufficient time to allow the entrained black liquor to separate. This gave a crude floating soap with an average solids content of about 65%. A measured amount of this crude floating soap was run into a mixing tank, the desired quantity of the proposed inhibitor was added thereto and the resulting mixture was agitated until uniformly blended. The blended mixture was fed between two revolving drums whose surfaces were maintained at a temperature of about 135° C.-150° C. The mixture was thus dried to a moisture content of about 5% (usually being 1%-5%) and then doctored off the drums in the form of very thin, hot, sticky, fluffy and discontinuous films. The dried floating soap mixture fell onto a screw conveyor from which it was picked up by a blower and sent to a cyclone separator. The dried and cooled floating soap mixture passed from the cyclone separator into multi-wall paper bags which were closed and sent to storage. Each bag was loaded with 50 pounds of the floating soap mixture.

In passing through the fan and cyclone separator in the presence of a large volume of air, the large plastic sticky, thin films of floating soap mixture coming from the drums were further dried, reduced in tackiness, cooled and disintegrated to a coarse powder in suitable form to be bagged. This product had a bulk density of 12-18 pounds per cubic foot.

Liquid additives which were soluble in water dissolved in the aqueous phase of the floating soap, and therefore these were dispersed without difficulty. Insoluble liquids became dispersed as a consequence of the emulsifying action of the floating soap. Insoluble solids were ground to a fine powder before blending in the floating soap. Salts and other soluble solids dissolved in the aqueous phase of the floating soap. Thus sodium thiosulfate, e. g., was incorporated by adding the crystals directly to the floating soap and agitating until a uniform blend was obtained.

EXAMPLE 2

Portions of the dried floating soap-inhibitor mixture from Example 1 above were obtained just prior to the bagging operation therein and further processed as follows.

This floating soap mixture was pressed into sheets of roughly $\frac{1}{16}$ " thickness by passing same between two opposing 8" diameter steel pressure rolls. The surfaces of the rolls were maintained at a temperature of about 40° C., which is approximately the temperature of the floating soap mixture discharging from the cyclone in Example 1. Then the sheets were broken up into relatively small flakes all of which passed a screen having $\frac{3}{8}$ " openings. This gave a compressed floating soap mixture having a bulk density of about 35 pounds per cubic foot and an absolute density of approximately 1.07 grams per cubic centimeter.

One roll was rotated by conventional driving means at a speed of about 4 R. P. M. The opposing roll idled and was rotated merely by the friction imparted by the driven roll through the floating soap mixture being pressed, the idling roll rotating at a speed slightly less than that of the driven roll.

In order to determine the comparative effect on spontaneous heating obtained by adding various inhibitors to floating soap in accordance with Example 1 above and by the dual treatment of adding various inhibitors to floating soap and pressing the resulting mixture in accordance with Example 2 above, the products of Example 1

and the products of Example 2 were evaluated by the Mackay test in the manner disclosed in Example 3 below.

EXAMPLE 3

Spontaneous heating tests

The Mackay test, with modifications indicated below, was employed on samples of the various products made according to Examples 1 and 2 above and their tendency to heat spontaneously thereby measured. This is a standard accelerated test originally developed for determining the spontaneous heating tendency of oils. See Scott, Standard Methods of Chemical Analysis, 5th edition, New York: D. Van Nostrand Co., Inc., page 1782.

In order to adapt the Mackay test to better meet the testing requirements of this invention, the test sample was placed in a wire gauze basket made of stainless steel and the basket was suspended in an air jacket immersed in a constant temperature oil bath. One end of a thermocouple was inserted into the center of the sample and the other end was connected to a temperature recorder. Bath temperatures of 110° C., 115° C., and 120° C. were used and the test periods were varied from 24 hours to 96 hours.

In the Mackay test the sample temperature gradually rises to bath temperature over a period of about 6 hours. Thereafter, if the sample is reactive (i. e. unstable toward spontaneous heating), its temperature will continue to rise gradually a few degrees above bath temperature and then its temperature will suddenly begin to rise rapidly, indicating that a vigorous exothermic reaction is taking place. If the sample is non-reactive (i. e. stable toward spontaneous heating), its temperature will remain at or only slightly above bath temperature.

The Mackay test is an accelerated test, designed to determine in a few hours what may be expected to occur during several days or weeks under practical storage conditions. In the Mackay test the sample is subjected to much more severe conditions than would be encountered in storage. Accordingly, whereas a mass of dried floating soap in storage may gradually rise to a temperature sufficiently high to damage the soap, a sample of the same material in the Mackay test will exhibit a sudden sharp rise in temperature after a few hours' exposure. In both cases, the soap particles are fused into a charred, useless mass.

Table 1 below gives the data and test conditions resulting from applying the Mackay test to floating soap made by adding various inhibitors thereto and then drying same (Example 1 above). Among other data, Table 1 shows the reaction temperature or temperature at which the sample began to react (column 5), the time which had elapsed under the test conditions when the reaction started (column 8), the maximum temperature the sample reached (column 6), the time which had elapsed when the sample reached its maximum temperature (column 9), and crossover or the time which had elapsed when the sample reached the bath temperature (column 7). The same headings as used in columns 4-9 of Table 1 are used, respectively, as headings for the last six columns of Table 2 below. Table 3 below gives data under the same headings as Tables 1 and 2 except columns 5 and 8 of Table 1 were not needed in Table 3 because none of the latter samples reacted or heated spontaneously. In the samples which exhibited the sudden temperature rise characteristic of the unstable material, the particles of the floating soap fused into a single lump, whereas the samples which did not react in this way remained free flowing after the test was completed.

The Mackay tests made on the samples of Tables 2 and 3 were supplemented by large scale tests in which 50 pound bags of floating soap inhibited with sodium thiosulfate were stored in large stacks and observed over periods of thirty days or more without witnessing any damage to the product due to spontaneous heating.

Tests on the samples of Table 1 and Table 2 containing no inhibitor were made as checks or blanks and comprised conventional dried floating soap without the benefit of any inhibitor or pressing. Tests on samples 1 and 2 of Table 3 were likewise made as checks or blanks but they comprised conventional dried granular floating soap which was pressed into flakes in accordance with our said copending application referred to hereinbefore.

In Table 3 below, the definition of certain of the inhibitors may be further defined as follows. The material 43D is a wood oil rich in phenols, with a boiling range of 200-300° C., which is obtained by vacuum distillation of the soluble tar separated from pyroligneous liquor during the refining of acetic acid and methanol. Pyroligneous liquor is the condensate recovered during destructive distillation of hardwoods. The material 65D is a wood oil rich in pyrogallol and its ethers, with a boiling range of 200-350° C., which is obtained by vacuum distillation of the raw settled tar which separates from the pyroligneous liquor produced in the destructive distillation of hardwoods. The ammoniated 43D and 65D are the reaction products obtained by a reaction of ammonia on 43D and 65D, respectively, at 100° C. Kraft liquor solids is the organic matter and salts contained in the liquor produced when pine wood is cooked by the kraft process. Precipitated kraft lignin is the material precipitated from spent kraft liquor when it is acidified with a mineral acid. "Oxidex" is a commercial antioxidant made by Fritzsche Brothers, Inc., 76 Ninth Avenue, New York city. "Oxidex" consists of a combination of aromatic ketones, alcohols, phenols and terpenes. "Ortholeum" 300 is a commercial antioxidant made by E. I. du Pont de Nemours & Company, Inc. of Wilmington, Delaware. "Ortholeum" 300 consists of a combination of derivatives of aromatic amines.

It will be apparent from Table 1 above that with one exception all of the samples heated spontaneously, i. e., out of the many inhibitors tested all but one failed to inhibit spontaneous heating in floating soap. That exception was sodium thiosulfate, sample #27, and it proved to be an excellent inhibitor. In view of this, only sodium thiosulfate was tested in Tables 2 and 3 below. Table 2 tests were made primarily to verify this surprising discovery.

The original data for Example 3 were obtained on a conventional circular recorder chart as continuous lines which were drawn by the automatic recorder connected to thermocouples in the samples under test, as mentioned in the first part of Example 3 above. The data in Tables 1, 2 and 3 above were obtained by reading off values at appropriate points on the original recorder charts. Fig. 1 of the drawing accompanying this application is a graphical representation of the curves drawn by the

automatic recorder when testing samples 14 and 18 of Table 2 and sample 8 of Table 3. These are shown as the dotted line curve, the dash line curve and the solid line curve, respectively, in the drawing.

EXAMPLE 4

A solution comprising 400 parts sodium hydroxide and 1900 parts water was prepared and heated to boiling. While the mixture was being well-agitated, 3200 parts of crude tall oil was slowly added, after which the soap was maintained at 100° C. for one hour while continuing to agitate. This produced a soft brown soap with an average solids content of about 65%. It had a pH of 10.5 when dissolved in water, and hence it did not contain excess alkali or tall oil. A measured amount of this tall oil soap was run into a mixing tank, the desired quantity of inhibitor was added thereto and the resulting mixture was agitated until uniformly blended. The blended wet mixture was fed between two revolving drums whose surfaces were maintained at a temperature of about 135° C.-150° C. The mixture was then dried to a moisture content of about 5% (usually being 1%-5%) and then doctored off the drums in the form of very thin, hot, sticky, fluffy and discontinuous films. The films were cooled and broken up into a coarse or granular powder in suitable form for bagging and commercial use. This product had a bulk density of about 15 pounds per cubic foot.

TABLE 4.—ADDING $\text{Na}_2\text{S}_2\text{O}_3$ TO TALL OIL SOAP—EFFECT ON SPONTANEOUS HEATING

EXAMPLE 5

Portions of the dried tall oil soap-inhibitor mixture ready for bagging from Example 4 above were obtained and further processed as follows.

This tall oil soap mixture was pressed into sheets of roughly $\frac{1}{16}$ " thickness by passing same between two opposing 8" diameter steel pressure rolls. The surfaces of the rolls were maintained at a temperature of about 40° C. Then the sheets were broken up into relatively small flakes all of which passed a screen having $\frac{3}{8}$ " openings. This gave a compressed tall oil soap mixture having a bulk density of about 32 pounds per cubic foot and an absolute density of approximately 0.95 gram per cubic centimeter.

One roll was rotated by conventional driving means at a speed of about 4 R. P. M. The opposing roll idled and was rotated merely by the friction imparted by the driven roll through the tall oil soap mixture being pressed, the idling roll rotating at a speed slightly less than that of the driven roll.

In order to determine the comparative effect on spontaneous heating obtained by adding inhibitors to tall oil soap in accordance with Example 4 above and by the dual treatment of adding inhibitors to tall oil soap and pressing the resulting mixture in accordance with Example 5 above, the products of Example 4 and the products of Example 5 were evaluated by the Mackay test in the manner disclosed in Example 6 below.

EXAMPLE 6

Spontaneous heating tests

Spontaneous heating tests were conducted on the tall

oil soaps of the invention in the manner described in Example 3 above. However, in these tests a single bath having a temperature of 120° C. was employed and the test periods were 36 hours.

Table 4 below gives the data and test conditions resulting from applying the Mackay test to tall oil soap made by adding sodium thiosulfate as an inhibitor thereto and then drying same (Example 4 above). Among other data, Table 4 shows the reaction temperature or 10 temperature at which the sample began to react (column 4), the time which had elapsed under the test conditions when the reaction started (column 7), the maximum temperature the sample reached (column 5), the time which had elapsed when the sample reached its 15 maximum temperature (column 8), and crossover or the time which had elapsed when the sample reached the bath temperature (column 6).

It should be noted in Table 4 below that sample 1 is 20 conventional unpressed tall oil soap containing no inhibitor, sample 2 is conventional unpressed tall oil soap containing $\text{Na}_2\text{S}_2\text{O}_3$ as an inhibitor, samples 3 and 4 are tall oil soap roll-pressed and made into flakes and are without and with the benefit of $\text{Na}_2\text{S}_2\text{O}_3$ inhibitor, respectively. Sample 1 exhibited the sudden temperature 25 rise characteristic of conventional unstable tall oil soap and the particles thereof fused into a single lump, whereas samples 2, 3 and 4 did not react in this way and remained free-flowing after the tests were completed.

It will be apparent from Table 4 above that we have obtained a very substantial improvement in stability 45 against spontaneous heating by adding $\text{Na}_2\text{S}_2\text{O}_3$ to conventional unpressed tall oil soap (sample 2), and that we have obtained a still greater reduction in spontaneous heating by the dual treatment (sample 4) of adding $\text{Na}_2\text{S}_2\text{O}_3$ to conventional tall oil soap and pressing the resulting mixture.

The original data for Example 6 were obtained on a 50 conventional circular recorder chart as continuous lines which were drawn by the automatic recorder connected to thermocouples in the samples under test, as mentioned 55 in the first part of Example 6 above. The data in Table 4 above were obtained by reading off values at appropriate points on the original recorder charts. Fig. 2 of the drawing accompanying this application is a graphical representation of the curves drawn by the automatic recorder when testing samples 1-4 of Table 4. These are shown as the dotted line curve, the X line curve, the dash line curve, and the solid line curve, respectively, in the drawing.

EXAMPLE 7

The tests recorded in Table 1 of Example 3 were 60 repeated with the sodium tallowate contemplated by the present invention. As in the case of floating soap, all of the multitude of inhibitors except $\text{Na}_2\text{S}_2\text{O}_3$ listed in Table 1 of Example 3 proved ineffective for inhibiting the tall oil soap against spontaneous heating. Only the thiosulfates of the present invention was effective as illustrated in Table 4 of Example 6.

The foregoing examples have been presented only for 75 the purpose of illustration and are not to be construed

as limiting the scope of the invention as generically described.

Conditions for practicing this invention in accordance with the preferred embodiments disclosed and/or exemplified above may be varied widely without departing from the spirit and scope of this invention. Instead of sodium thiosulfate, it is apparent that any of the other alkali metal thiosulfates and ammonium thiosulfates may be employed. This follows from the well-known chemical equivalence of the alkali metal thiosulfates. All of these compounds are substantially equally effective for the purposes of the invention. However, use of sodium thiosulfate is preferred because of its lower cost and greater availability.

The quantity of inhibitor employed is not critical, but it may vary over a broad range. The amount of inhibitor employed depends on a number of factors, two of which are the length of time and the degree of stabilization desired. If the soap does not heat spontaneously when subjected to the Mackay test, it is considered adequately stabilized for all practical purposes. It has been found that from 1% to 3% by weight, on the dry basis of the floating soap or tall oil soap, produces satisfactory results and incorporation of from about 2% to about 3% by weight is preferred. Although additional thiosulfate may be employed, it appears that there is little to be gained by addition of increased amounts. For example, tests made with 5% sodium thiosulfate exhibited no noticeable improvement over those made with 3% sodium thiosulfate. While the use of less than about 1% inhibitor reduces spontaneous heating and the use of quantities below 1% are within the scope of this invention, the reduction in spontaneous heating at this lower concentration is not as great as that desired for most industrial purposes.

Since the mechanisms involved in the stabilization effected by the present invention are unknown, it is not possible to explain why the thiosulfates contemplated by the invention are excellent inhibitors for spontaneous heating of floating soaps and tall oil soaps, whereas the many other materials which have been employed successfully by the prior art to inhibit oxidation of compositions such as resins, plastics, toilet soaps, and the like, are of no value as inhibitors of spontaneous heating in floating soap and tall oil soap. One possible reason for the unexpected behavior of the inhibitors of the invention is that tall oil soap and floating soap are so different from other materials that they are in a class by themselves as compared with the compositions treated by prior art methods. Possibly the inhibitors of the present invention do not, as such, do the inhibiting but instead become associated with or combine with one or more of the varied constituents comprising the very complex mixture in the floating soap or the tall oil soap and the material thereby formed effects the stabilization. This hypothesis is offered merely as a possible explanation of the unusual results obtained by this invention and it is not intended as any limitation of the scope of the invention as disclosed and claimed.

Since it is apparent that widely different embodiments of this invention may be practiced without departing from the spirit and scope thereof, it is to be understood that the invention is limited only by the scope of the appended claims.

This application is a continuation-in-part of copending applications Serial No. 495,519, filed March 21, 1955, now abandoned, and Serial No. 554,682, filed December 22, 1955, now abandoned.

What is claimed is:

1. A soap product inhibited against spontaneous heating consisting essentially of a material selected from the group consisting of floating soap and tall oil soap obtained by concentration of black liquor resulting from

pulpwood digestion processes and containing at least a substantial portion of the impurities naturally present therein, and, as the sole essential inhibitor, an inhibiting amount of a material selected from the group consisting of alkali metal and ammonium salts of thiosulfuric acid.

5 2. The process for producing a soap product inhibited against spontaneous heating which consists essentially of blending with a material selected from the group consisting of floating soap and tall oil soap obtained by concentration of black liquor resulting from pulpwood digestion processes and containing a substantial portion of the impurities naturally present therein, as the sole essential inhibitor, an inhibiting amount of a material selected from the group consisting of the alkali metal and ammonium salts of thiosulfuric acid.

10 3. The floating soap of claim 1 wherein said inhibitor is sodium thiosulfate.

4. The floating soap of claim 1 wherein said inhibitor is potassium thiosulfate.

20 5. The floating soap of claim 1 wherein said inhibitor is ammonium thiosulfate.

6. A substantially dry, compressed soap product inhibited against spontaneous heating consisting essentially of a material selected from the group consisting of floating soap and tall oil soap obtained by concentration of black liquor resulting from pulpwood digestion processes and containing at least a substantial portion of the impurities naturally present therein and containing, as a sole essential inhibitor against spontaneous heating, an inhibiting amount of a material selected from the group consisting of the alkali metal and ammonium salts of thiosulfuric acid, said soap having an absolute density of at least about 0.95 g./cc.

30 7. The floating soap of claim 6 wherein said inhibitor is sodium thiosulfate.

35 8. The floating soap of claim 6 wherein said inhibitor is potassium thiosulfate.

9. The floating soap of claim 6 wherein the inhibitor is ammonium thiosulfate.

10. The process for producing a substantially dry soap product inhibited against spontaneous heating which consists essentially of blending with a material selected from the group consisting of floating soap and tall oil soap obtained by concentration of black liquor resulting from pulpwood digestion processes and containing at least a substantial portion of the impurities naturally present therein and while said soap is in a particulate moist condition, as the sole essential inhibitor, an inhibiting amount of a material selected from the group consisting of the alkali metal and ammonium salts of thiosulfuric acid, and drying the resulting blend.

45 11. The process of claim 2 wherein said inhibitor is sodium thiosulfate.

12. The process of claim 2 wherein said inhibitor is potassium thiosulfate.

50 13. The process of claim 2 wherein said inhibitor is ammonium thiosulfate.

14. The process for preparing a soap product inhibited against spontaneous heating which consists essentially of blending with a material selected from the group consisting of floating soap and tall oil soap produced by concentration of black liquor resulting from pulpwood digestion processes, as the sole essential inhibitor, an inhibiting amount of a material selected from the group consisting of the alkali metal and ammonium salts of thiosulfuric acid, and drying and compressing the resulting blend to an absolute density of at least about 0.95 g./cc.
